UNITED STATES PATENT OFFICE.

ANDREW FREDERICK, OF HARMONY, PENNSYLVANIA.

TRACTOR.

1,089,698.

Specification of Letters Patent. Patented Mar. 10, 1914.

Application filed March 5, 1913. Serial No. 752,199.

To all whom it may concern:

Be it known that I, ANDREW FREDERICK, a citizen of the United States, residing at Harmony, in the county of Butler and State of Pennsylvania, have invented a new and useful Tractor, of which the following is a specification.

This invention relates to tractors and more particularly to a machine of this character having a single combined steering and propelling wheel, the said machine being adapted to be coupled to plows, harrows, and other machines so as to draw them forward and being likewise adapted to be fixedly connected to the front of any machine to be actuated so as to constitute practically an integral part thereof.

A further object is to provide a machine of this character the motor of which constitutes means both for actuating the propelling wheel and for steering.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

85 In said drawings:—Figure 1 is a plan view of the machine. Fig. 2 is a view partly in section and partly in side elevation. Fig. 3 is a section on line A—B Fig. 2, the drive shaft, its gear and sprocket, and a portion 40 of the wheel being shown in elevation. Fig. 4 is a plan view of the brake mechanism.

Referring to the figures by characters of reference 1 designates the side beams of the frame of the structure, said side beams having upwardly and inwardly converging portions 2 which, in turn, merge into forwardly extending portions 3 secured in any suitable manner against the sides of a head block 4. An opening 5 extends through the head 40 block to receive the tubular stem 6 extending upwardly from the head 7 of a yoke 8. This head is formed with a segmental gear 9 which meshes with a worm 10 carried by a shaft 11. Said shaft extends along one side 55 of the frame of the machine and preferably through one of the upwardly extending por-

tions 2, there being a sprocket 12 upon the rear end portion of the shaft and which receives motion, through a chain 13, from another sprocket 14 secured to a shaft 15 extending horizontally and mounted within suitable bearings. This shaft 15 has oppositely disposed conical friction gears 16 and a lever 17 is connected to the shaft and constitutes means whereby the shaft can be shifted longitudinally so as to bring either of said friction gears into contact with a friction disk 18 driven by the motor 19. A vertical shaft 20 is mounted upon the frame of the tractor and has oppositely disposed friction gears 21 arranged above and below shaft 15. A bell crank lever 22 is connected to the shaft and is adapted to be actuated by a link 23 extending to a lever 24. By pulling the lever in one direction, the link 75 will shift the bell crank lever so as to move the shaft 20 upwardly whereas, when the lever 24 is moved in the opposite direction, shaft 20 will be caused to shift downwardly. Thus either of the gears 21 can be brought 80 in contact with the disk 18. Instead of raising and lowering shaft 20 by means of a lever such as shown, a foot lever 25, which is fulcrumed at 26, can be connected to the lower end portion of the shaft and can be 85 provided with a foot plate 27. By pushing downwardly on the foot plate, the other end of the lever will pull downwardly on shaft 20. A brake wheel 28 can be secured to the lower end portion of shaft 20 and provided 90 with a brake band 29 extending to a foot lever 30. When this lever is depressed, the band will be tightened on the wheel and the rotation of shaft 20 thus retarded or stopped.

Secured to the upper end of shaft 20 is 95 a sprocket 31 adapted to transmit motion through a chain 32 to another sprocket 33 secured to the upper end of a shaft 34. This shaft is journaled within the tubular stem 6 and extends downwardly to one side 100 of a propelling wheel 35, there being a bracket 36 extending inwardly from one side of the yoke 8 and in which the lower end of shaft 34 is journaled. Propelling wheel 35 is preferably provided with a 105 broad tread and is connected to the yoke 8 by an axle 37. A large gear 38 is connected to or formed with one side of the wheel and is constantly in mesh with a small drive gear 39 secured to the lower end portion 110 of the shaft 34. Wheel 35 has radially disposed webs 40 constituting spokes and

weights 41 are adapted to be placed within the wheel so as to make the wheel as heavy as desired.

A collar 42 may be secured to the stem 6 above the head block 4 and anti-friction devices such as indicated at 43 may be interposed between this collar and the head block and between the head block and the top of the yoke 8.

When it is desired to use the machine as a tractor complete in itself, supporting wheels 44 are connected to the rear portions of the side beams 1. Thus the machine can be used for pulling other machines. If desired, however, the side beams 1 can be bolted or otherwise secured directly to the machine to be drawn and in this event the wheels 44 are to be entirely removed.

By shifting one of the friction gears 21 into contact with the disk 18 motion will be transmitted from said disk to the shaft 20 and through sprocket 31, chain 32 and sprocket 33, to shaft 34. Gear 39 will thus actuate the large gear 38 and cause the wheel 35 to rotate. By shifting the shaft 20 in the opposite direction, the other gear 21 will be brought into contact with the disk 18 and the movement of the machine reversed. Should it be desired to steer the tractor, one of the gears 16 is shifted into contact with the disk 18 and motion is thus transmitted from said disk and through the friction gear to the shaft 15 and thence through sprocket 14, chain 13 and sprocket 12 to shaft 11. The worm 10 will therefore be caused to actuate the segmental gear 9 and the yoke 8 will be turned about the longitudinal axis of the stem 6. By shifting shaft 15 in the opposite direction, the yoke 8 can be caused to turn in the other direction. Thus it will be seen that by manipulating the two levers 17 and 24, the tractor can be both propelled and steered by the motor. It is designed to so arrange the levers 17 and 24 that they can be conveniently reached by a person occupying the seat ordinarily

provided upon the agricultural machine, wagon or the like to be drawn by the tractor.

It is preferred to arrange two sprockets 50 upon each shaft 20 and 34, one sprocket of each pair being larger than the other. In the drawings a supplemental sprocket 45 has been shown mounted on the shaft 20 and another supplemental sprocket 46 has been 55 shown mounted on the shaft 34. Thus it will be seen that by interchanging the sprockets the speed of the tractor can be varied. The sprockets of each pair are preferably formed in one piece. 60

Idler rollers 47 may be arranged under the chain 32 at any desired points so as to prevent it from sagging.

A guard plate may, if desired, be secured to the yoke 8 for the purpose of protecting 65 gear 38. Thus the gear can be made much larger and therefore brought nearer the ground, this consequently increasing the power.

Instead of utilizing the friction gears 21, 70 any other suitable power transmitting means may be used.

What is claimed is:—

A tractor including a frame, a motor supported thereby, wheels for supporting the 75 frame close to the ground, said frame having an upwardly extending end portion, a relatively large combined propelling and steering wheel arranged under and supporting said upwardly extending portion of the 80 frame, a revoluble drive member actuated by the motor, and separately operated means co-operating with said member for rotating the drive wheel in either direction and for steering said wheel respectively. 85

In testimony that I claim the foregoing as my own, I have hereto affixed my signature in the presence of two witnesses.

ANDREW FREDERICK.
